UNITED STATES PATENT OFFICE.

FRANZ CARL KÜHNE, OF CHARLOTTENBURG, GERMANY.

TRAIN-ARRESTER.

No. 899,602.

Specification of Letters Patent.

Patented Sept. 29, 1908.

Application filed February 17, 1908. Serial No. 416,288.

To all whom it may concern:

Be it known that I, FRANZ CARL KÜHNE, a subject of the German Emperor, residing at Charlottenburg, near Berlin, in Germany, have invented a certain new and useful Train-Arrester, of which the following is a specification.

Rail-brakes are already known, with an arrangement of levers adapted to be actuated by a suitable device for the purpose of simultaneously covering both rails with sand. Sand-tracks have also already been used to destroy the momentum of trains.

The present invention resides in the device which will be hereinafter specified in the claims, and which allows of producing a sand-track in a reliable manner to stop, in case of need, an entire train.

The apparatus is illustrated as a cross sectional diagram in the annexed drawing.

1 represents the outlines of the cars, 2 the clearance outlines thereof. A section of the rails 3, proportional to the momentum of the train to be stopped, is arranged in troughs 4 of angle-iron, which are filled with sand to the height of the upper rail-head, and which do not appreciably impede a train traveling at normal speed. Receptacles 6 hinged at 5 to the outer edges of the troughs also contain sand. Both the said receptacles are connected by levers 7 to a weight 8 which is normally held in an elevated position by a suitable device, and the receptacles are held in horizontal positions while the weight is in its elevated position. The release of the weight causes the receptacles, however, to swing upwards into the positions indicated in the drawing by dotted lines, so that the sand is emptied into the troughs. Before the train arrives the empty receptacles must be swung back to their horizontal positions, in order to provide the normal clearance.

Various means may be used for lifting the weight and holding it in its elevated position, for example a hydraulic cylinder or compressed air cylinder 9, or an electro-magnet.

In case of need a lever 10 is actuated by a suitable device, for example automatically by a train in the known manner, and actuates a controlling device in the conduit 11 so that the weight 8 is released and the receptacles 6 are tilted. Reversal of the controlling device 12 causes the weight to be lifted again, so that the empty receptacles 6 return to their normal positions.

What I claim as my invention and desire to secure by Letters Patent of the United States is:

1. A train arrester comprising in combination a railroad track, sand receptacles hinged adjacent to said track and means for tilting said receptacles towards the rails for discharging sand thereon.

2. A train arrester comprising in combination a railroad track, troughs containing the rails of said track, sand receptacles hinged adjacent to said track and means for tilting said receptacles towards the rails for discharging sand thereon.

3. A train arrester comprising in combination a railroad track, sand receptacles hinged adjacent to said track and means for tilting said receptacles towards the rails for discharging sand thereon comprising a weight, a cylinder, a piston in said cylinder for holding said weight, and means for releasing the fluid pressure from said cylinder.

In witness whereof I have signed this specification in the presence of two witnesses.

FRANZ CARL KÜHNE.
